UNITED STATES PATENT OFFICE.

ALFRED H. JOHNSON, OF NILES, MICHIGAN, ASSIGNOR TO NATIONAL-STANDARD COMPANY, OF NILES, MICHIGAN.

LIFTING-JACK.

1,381,125.

Specification of Letters Patent. Patented June 14, 1921.

Application filed December 11, 1920. Serial No. 429,993.

To all whom it may concern:

Be it known that I, ALFRED H. JOHNSON, a citizen of the United States, residing at Niles, county of Berrien, and State of Michigan, have invented certain new and useful Improvements in Lifting-Jacks, of which the following is a specification.

This invention relates to improvements in lifting jacks.

10 The main objects of this invention are:—

First. To provide in a lifting jack of the reversing type an improved reversing control means.

15 Second. To provide an improved lifting jack of the reversing type which is very conveniently and easily operated.

Further objects and objects relating to structural details, will definitely appear from the detailed description to follow.

20 I accomplish the objects of my invention by the devices and means described in the following specification. The invention is clearly defined and pointed out in the claims.

25 A structure which is a preferred embodiment of my invention is clearly illustrated in the accompanying drawing, forming a part of this specification, in which:

Figure I is a detail side elevation of a 30 lifting jack embodying the features of my invention, parts being broken away for convenience in illustration, the reversing means being shown in inoperative position.

Fig. II is a detail side elevation correspond to Fig. I with the reversing means in 35 operative position.

Fig. III is a detail view of the inner end of the actuating lever showing the arrangement of the lifting pawl thereon.

40 Fig. IV is a detail transverse section through the actuating lever on line corresponding to line 4—4 of Fig. I.

Fig. V is a detail side elevation partially in section on line corresponding to line 5—5 45 of Fig. VI showing the embodiment or adaptation of my improvements to another form of jack.

Fig. VI is a detail view partially in section on line corresponding to line 6—6 of 50 Fig. 5.

In the drawing similar reference characters refer to similar parts throughout the

several views, and the sectional views are taken looking in the direction of the little arrows at the ends of the section lines.

55

Referring to the drawing, the frame 1 is provided with a lifting bar 2. The lifting bar is provided with a rack 3 with which pinion 4 coacts; the pinion being secured to the ratchet wheel 5.

60

The ratchet wheel 5 is driven from the pawl 6 mounted on the inner end of the actuating levers 7 pivoted at 8. The pivot pin 9 for the lever 7 is mounted on the frame. The holding pawl 10 is pivoted on the frame 11 to coact with the ratchet wheel 5. The pawls are held yieldingly in engagement with the ratchet by means of the springs 12, the springs being mounted on the stud 13 and engaging the pins 14 on the pawls.

70

The reversing member 15 is pivoted at 16 and provided with upwardly projecting arms 17 and 18, the arm 17 being adapted to coact with a pin 19 on the pawl 6 and the arm 18 with the pin 14 of the pawl 10 when the reversing member is in operative position. The reversing member is actuated by the spring 21, the strength of which exceeds that of the springs 12, so that in operation it overcomes the tension of the pawl springs, alternately throwing the pawls out of engagement with the ratchet wheel when they are freed from the load by the manipulation of the lever. The action of the reversing member on the pawls is that of the structure shown in the patent to Cook No. 940,433, dated November 16, 1909.

85

The actuating lever 7 comprises a hollow shank portion 22 and a handle extension portion 23. This handle extension portion may be rotated in the shank portion and is provided with a spiral groove 24 engaged by the pin 25, so that upon rotation of the handle a longitudinal movement is imparted thereto. The handle acts upon the control member 26 which is slidable within the shank, the control member being slotted at 27 to engage the lever pivot 29 whereby it is retained in position. The control member engages the reversing member as shown in Fig. I, so that when the handle 23 is turned in one direction, the reversing member is shifted to and held or locked in an inoperative position, as shown in Fig. I, and when

90

95

100

turned in the other direction the control member is released, as shown in Fig. II.

In the embodiment shown in Figs. V and VI the pawls 30 and 31 coact directly with the lifting bar 32 which is provided with ratchet teeth 33. The pawls 30 and 31 are provided with tripping fingers 34 and 35 respectively, the fingers being pivotally mounted on the pawls and provided with springs 36 and 37.

The pawl 30 is mounted on the actuating lever, while the pawl 31 is mounted on the frame. The reversing member 38 is pivoted at 39 and provided with an actuating spring 40. The reversing member is held in inoperative position by the same means as described. The reversing member is provided with an inwardly projecting arm 41 to be engaged by the control member 26, as shown in Fig. VI. The finger 34 coacts with an inclined surface on the reversing member, indicated by the dotted line 42 when the pawl is lowered, thereby throwing the pawl out of engagement with the rack as soon as the load is released from the pawl, the swinging of the finger by its engagement with the inclined surface placing the spring 36 under pressure. On the upward movement of the pawl 30 or on the down stroke of the actuating lever, the pin 43 comes into contact with the tripping lever 44, pivoted at 45 on the tripping finger 35. The lower end of the lever 44 engages the projection 46 on the reversing member, thereby actuating the tripping finger 35 to place its spring under stress, so that as soon as the load is released from the pawl 31 it is disengaged.

The particular details of this tripping mechanism, however, are not features of my present invention, and I have illustrated the same in this connection in order to show the adaptability thereof to different forms of jacks.

My improved lifting jack is very convenient to use, as for instance, as an automobile jack, as the jack may be reversed from the end of the operating lever.

I have illustrated and described two embodiments or adaptations of my improvements. While I contemplate several other adaptations, it is believed that the disclosure made will enable those skilled in the art to adapt the same as may be desired.

Having thus described my invention, what I claim as new and desire to secure by Letters Patent, is:

1. In a lifting jack comprising a frame and lifting bar, the combination of a pair of alternately acting pawls provided with engaging springs, a pivotally mounted reversing member adapted to coact with said pawls, a spring arranged to actuate said reversing member, said spring being of greater strength than the engaging spring of said pawls, an actuating lever, one of said pawls

being mounted on said lever, said lever comprising a hollow shank portion pivoted on said frame and a handle portion rotatively mounted in said shank, said handle being provided with a spirally disposed groove 70 and said shank having a pin engaging said groove, whereby when the handle is rotated it is moved longitudinally within the shank, and a control member for said reversing member disposed in said shank for sliding 75 adjustment therein to coact with said handle.

2. In a lifting jack comprising a frame and lifting bar, the combination of a pair of alternately acting pawls, a pivotally mounted reversing member adapted to coact 80 with said pawls, an actuating lever, one of said pawls being mounted on said lever, said lever comprising a hollow shank portion pivoted on said frame and a handle portion rotatively mounted in said shank, said handle being provided with a spirally disposed groove and said shank having a pin 85 engaging said groove whereby when the handle is rotated it is moved longitudinally within the shank, and a control member for 90 said reversing member disposed in said shank for sliding adjustment therein to coact with said handle.

3. In a lifting jack comprising a frame and lifting bar, the combination of a pair of 95 alternately acting pawls, a reversing member adapted to coact with said pawls, an actuating lever operatively associated with at least one of said pawls, and comprising a hollow shank portion pivoted on said 100 frame, and a handle portion rotatively mounted in said shank, said handle being provided with coengaging parts whereby when the handle is rotated it is moved longitudinally within the shank, and a longitudinally slotted control member for 105 said reversing member disposed in said shank for sliding adjustment therein to coact with said handle, and a pin on said shank engaging said slot in said control member. 110

4. In a lifting jack comprising a frame and lifting bar, the combination of a pair of alternately acting pawls, a reversing member adapted to coact with said pawls, an actuating lever operatively associated with 115 at least one of said pawls, and comprising a hollow shank portion pivoted on said frame and a handle portion rotatively mounted in said shank, said handle being provided with coengaging parts, whereby when the handle is rotated it is moved longitudinally within the shank, and a control member for 120 said reversing member mounted on said shank.

5. In a lifting jack comprising a frame and a lifting bar, the combination of a pair 125 of alternately acting pawls provided with engaging springs, a reversing member adapted to coact with said pawls, a spring arranged to act on said reversing member, said spring being of greater strength than the 130

engaging strength of said pawls, and an operating means for said jack, comprising a lever having a handle portion adapted for rotative movement and operatively associated with said reversing member, wherebv

5 it may be held in inoperative position.

In witness whereof I have hereunto set

my hand and seal in the presence of two witnesses.

ALFRED H. JOHNSON. [L. S.]
